US0D1092479S

(12) **United States Design Patent** (10) Patent No.: **US D1,092,479 S**
(45) Date of Patent: ** Sep. 9, 2025

(54) **DOUBLE STACK MULTIPORT FOR
MAKING OPTICAL CONNECTIONS**

(71) Applicant: **CORNING RESEARCH &
DEVELOPMENT CORPORATION**,
Corning, NY (US)

(72) Inventors: **Edward Wilson Licitra**, Decatur, GA
(US); **Matthew Wallace Peterson**, San
Francisco, CA (US); **Joel Christopher
Rosson**, Hickory, NC (US); **Jonathan
Patrick Summers**, Atlanta, GA (US);
Dayne Wilcox, El Cerrito, CA (US)

(73) Assignee: **CORNING RESEARCH &
DEVELOPMENT CORPORATION**,
Corning, NY (US)

(**) Term: **15 Years**

(21) Appl. No.: **29/833,172**

(22) Filed: **Apr. 1, 2022**

CLAIM

The ornamental design for a double stack multiport for making optical connections as shown and described.

DESCRIPTION

FIG. 1 is a front perspective view of a first embodiment of a double stack multiport for making optical connections showing our new design;

FIG. 2 is a top view thereof of FIG. 1;
FIG. 3 is a bottom view thereof of FIG. 1;
FIG. 4 is a right side view thereof of FIG. 1;
FIG. 5 is a left side view thereof of FIG. 1;
FIG. 6 is a front view thereof of FIG. 1; and
FIG. 7 is a rear view thereof of FIG. 1.
FIG. 8 is a front perspective view of a second embodiment
of a double stack multiport for making optical connections
showing our new design;
FIG. 9 is a top view thereof of FIG. 8;
FIG. 10 is a bottom view thereof of FIG. 8;
FIG. 11 is a right side view thereof of FIG. 8;
FIG. 12 is a left side view thereof of FIG. 8;
FIG. 13 is a front view thereof of FIG. 8; and,
FIG. 14 is a rear view thereof of FIG. 8.
In FIGS. 1-14, the evenly-spaced broken lines are included
for the purpose of illustrating environmental structure and
form no part of the claimed design.
